UNITED STATES PATENT OFFICE.

RICHARD M. PANCOAST, OF CAMDEN, NEW JERSEY.

WINDOW-VENTILATOR.

1,168,959.

Specification of Letters Patent.

Patented Jan. 18, 1916.

Application filed March 3, 1915. Serial No. 11,699.

To all whom it may concern:

Be it known that I, RICHARD M. PANCOAST, a citizen of the United States, residing at Camden, in the county of Camden and State 5 of New Jersey, have invented certain new and useful Improvements in Window-Ventilators, of which the following is a specification.

The object of the invention is the provision of an improved species or type of air inlet window ventilator which shall be of simple construction, cheap in first cost, very strong and rigid so it will not easily become broken or deformed, which shall have the 10 greatest air inlet capacity for the quantity of material used in its construction, which shall be of relatively small dimensions, especially in thickness, so as to occupy but little space and present the least obstruction to the 15 entrance of light, which may be adapted for application to different windows where the distance between the jambs varies, and which, withal, shall constitute a superior 20 means for admitting air to the interior of a room and deflecting it upwardly for the 25 purpose of ventilation.

The invention consists in certain novelties of construction and combinations of parts as herein set forth and claimed.

The accompanying drawings illustrate 30 three slightly different embodiments of the invention adapted for use inside a window, outside a window, and directly beneath a window sash, each constructed according to 35 the best mode of procedure I have so far devised for the purpose, also several modifications in details.

Figures 1 and 2 are vertical cross sections of part of a window frame, lower window 40 and one form of my air inlet ventilator which is located inside the window sash and upon the inside window sill; Fig. 1 showing the window raised and Fig. 2 showing the same lowered. Fig. 3 is a perspective view 45 of the ventilator as a whole. Fig. 4 is a plan view of a cut metal blank ready for bending to constitute the body part of a ventilator. Fig. 5 is an end view in elevation of the body part made by bending the blank of Fig. 4 50 on the longitudinal and vertical dotted lines thereof. Fig. 6 is a view in perspective of one of the metallic end pieces which are riveted or soldered upon the ears at the opposite ends of the body part. Figs. 7 and 8 55 are views similar to Figs. 1 and 2 with the ventilator located outside the window sash

and upon the outside window sill, the window being raised in one figure and lowered in the other. Fig. 9 is a top plan view of the ventilator shown by Figs. 7 and 8 located outside the window. Fig. 10 is a plan view of a cut out metal blank ready for bending on the dotted lines to form the body part of the ventilator shown by Figs. 7, 8 and 9. Fig. 11 is an inside elevation view of the 60 lower part of a window frame and window showing the window raised and my ventilator located beneath the window sash. Fig. 12 is an enlarged cross section of Fig. 11 on line $x-x$. Figs. 13 and 14 are views in perspective 65 showing different constructions of end extensions from the main body part of the ventilator.

Each of the three species of the ventilator shown, to wit: for use inside the window, 70 outside the window, and beneath the window sash, is comprised in the preferred form of five pieces only: a sheet metal body part, two metallic end pieces, and two wooden pieces secured to the two metallic end pieces. 80 A metallic end piece and wooden piece in connection therewith is termed an extension.

The ventilator for use inside the window sash upon the inside window sill, and shown by Figs. 1, 2, 3, 4, 5 and 6 will first be described.

From a piece of suitable sheet metal is fashioned by cutting or cutting and punching the blank shown by Fig. 4, wherein the numeral 1 designates ears (a, b, c, d, e); 2, 90 rows of holes; 3, top and bottom edges of the blank; and the longitudinal and vertical dotted lines the lines on which the blank is to be bent. First, the edges 3 are turned over through the arcs of 180° upon the body 95 of the blank, or, if preferred, around a wire to form smooth reinforced edges; secondly, the blank is bent on the longitudinal dotted lines to form alternate oblique and horizontal parts, as shown by dotted lines, Fig. 5, 100 the horizontal parts having the holes for the admission of air and the under surfaces of the oblique parts serving to deflect and direct the air inwardly and upwardly; thirdly, the ears are bent at right angles to the positions shown in Fig. 5, the top ears being 105 bent outwardly, the next ears below inwardly, and so on; fourthly, the metallic end pieces 4 having wings 5 are soldered on or secured by rivets 6 to the ears at opposite 110 ends of the fashioned body parts; and finally the wooden parts 7 of the extension

are secured by nails or screws between the wings 5 of the end pieces. Holes for rivets are shown in Figs. 5 and 6.

The ventilator for use outside the window and upon the outside window sill, illustrated by Figs. 7, 8, 9 and 10, is in construction substantially like that described, and the body part is fashioned from a similar blank shown by Fig. 10. The dotted lines indicate the lines for bending; 3, the edges to be turned over to strengthen the ventilator body; *a*, *b*, *c*, *d*, *e*, the ears; and 8, two rows of staggered holes which may be used for the admission of air in lieu of a single row of larger diameter. It will be observed that the ears of Fig. 10 differ slightly from those shown by Fig. 4. In bending them the ears *e* are bent inwardly, the next ears *d* are bent outwardly, then ears *c* inwardly, *b* outwardly, and *a* inwardly, which results in closing the spaces between the ends of the oblique and horizontal parts of the body portion when fashioned. In Fig. 4 the ears are bent in the reverse order, as shown by Fig. 5. As the lower edges of the extensions in this example must fit the beveled surface of the outer window sill, portions of the material are cut away to form beveled surfaces at the ends of the ventilator which will match the bevel of the window sills.

Referring to Fig. 9, where the ventilator is shown in top plan view, it will be observed that the wooden pieces 7, forming parts of the end extensions, are notched at 9 to receive the parting strips 10 and that the extreme ends of pieces 7 are widened at 11 to fill the outer window run spaces whereby the ventilator is securely held against displacement when once placed in position.

The ventilator to be used directly beneath the window sash shown by Figs. 11 and 12 has the body part fashioned from a blank similar to those described. However, the lower and top surfaces of the wooden parts of the extensions 7 and the end pieces 4 should be beveled to match the inclined surface of the outer window sill and the inclined surface of the bottom of the window sash. In other words, the extensions should be rhomboidal in cross section.

It will be observed that this type of ventilator has the same thickness as the width of the window sash runs, or, in other words, the same thickness as the window sash.

Figs. 13 and 14 illustrate two modified forms of extensions from the ends of the body part of the ventilator, additional to the form shown by Fig. 3. This feature of the invention which provides for adapting a ventilator for different widths of window frames and windows is of importance for the following reason: Window frame and sash manufacturers' stock sizes of window sashes are from $24\frac{1}{2}$ " to $34\frac{1}{2}$ " in width, but the most used are from $28\frac{1}{2}$ " to $34\frac{1}{2}$ " in

width, a difference of 6". My ventilators may be made in stock sizes to fit beneath sashes having a difference in width, for example, of 6" by constructing them as shown by Figs. 3, 13 and 14, where the extreme length of each ventilator is $34\frac{1}{2}$ ", which will fit under the widest stock size window sash. To adapt the ventilator shown by Fig. 3 for use under a sash $28\frac{1}{2}$ " wide 3" of material is cut or sawed off the wooden end of each extension. To attain the same end the extension may be made adjustable, that is, one part movable relative to another part, as shown by Fig. 13, where the metallic end pieces 12 secured to the ears of the body of the ventilator are made hollow and the pieces 13 of wood or other material slide inwardly and outwardly to increase or diminish the length of the ventilator as a whole so it will fit the desired opening therefor.

Fig. 14 illustrates a third way of increasing or diminishing the length of the ventilator as a whole, one end extension being like those of Fig. 3 and the opposite end provided with a wooden or metallic piece 14 riveted to the ears of the body part of the ventilator and a hollow metallic part 15 loosely fitting over and sliding upon the piece 14, as is obvious.

The ventilators for use inside the sash, outside the sash, and beneath the sash may be constructed in the way above described to adapt them for frames where the distances between the jambs are different. However, it should be understood that specific sizes of any type of the ventilator may be made to fit windows of any specific dimensions.

Obviously, I have provided a very simple and effective window ventilator which fulfills all the conditions set forth as the purpose of the invention. The saving in material, lightness in weight, and cheap first cost are especially noteworthy. The type for use under the sash where the width of the inner window runs is $1\frac{1}{2}$ " is of the same dimension, $1\frac{1}{2}$ " in thickness, and the types for use inside and outside the window sash are of substantially the same thickness, though they may be of greater dimension.

Where it is desired to admit more air it is preferable that the height only of the ventilator be increased, that is, a greater number of horizontal and deflecting plates in the body of the ventilator are to be provided, but the thickness of the ventilator may be increased to attain the same end.

In embodying the invention modifications in the shapes of the holes for the admission of air, in the shapes of the ears and the bending of the same, in the number of the oblique deflectors and horizontal parts constituting the body portion of the ventilator, and in the size and dimensions of the com-

plete ventilator may be made without constituting substantial departures.

What I claim is:

1. A window ventilator comprised of a main body portion of sheet metal having integral ears at the ends, air admission perforations and air deflectors, and extensions in connection with the ears at the ends; the said main body portion and ears being formed of a single sheet of metal having parallel lines of perforations and the projecting ears, the metal being bent lengthwise on lines each side of the lines of perforations to form alternate longitudinal air deflecting and air admission parts angularly disposed to one another, the integral ears bent at right angles to the said longitudinal parts, and the extensions secured to the ears at opposite ends of the body portion.
2. A window ventilator comprised of a main body portion of sheet metal having integral ears at the ends, air admission perforations and air deflectors; metallic end pieces; and extensions in connection with the metallic end pieces; the said main body portion and ears being formed of a single sheet of metal having parallel lines of perforations and the projecting ears, the metal being bent lengthwise on lines each side of the lines of perforations to form alternate longitudinal air deflecting and air admission parts angularly disposed to one another, the integral ears being at right angles

to the said longitudinal parts, the said metallic end pieces secured to the ears at each end, and the extensions secured to the metallic end pieces.

3. A window ventilator comprised of a main body portion of sheet metal having a plurality of air deflecting and perforated air admission parts angularly and longitudinally disposed relative to one another, ears at the ends of the said body portion, and extensions in connection with the ears.

4. A window ventilator comprised of a main body portion of sheet metal having a plurality of air deflecting and perforated air admission parts angularly and longitudinally disposed relative to one another, ears at the ends of the body portion, metallic end pieces secured to the ears, and additional pieces in connection with the end pieces.

5. A window ventilator comprised of a main body portion of sheet metal having a plurality of air deflecting and perforated air admission parts angularly and longitudinally disposed relative to one another, integral ears at the ends of the body portion, end pieces secured to the ears, and wooden pieces in connection with the end pieces.

In testimony whereof I affix my signature, in presence of two witnesses.
